US0D1004083S

(12) **United States Design Patent** (10) Patent No.: **US D1,004,083 S**
(45) Date of Patent: ** Nov. 7, 2023

(54) **CLIP FOR A GAS SAMPLING LINE**(71) Applicant: **Fisher & Paykel Healthcare Limited**,
Auckland (NZ)(72) Inventors: **Samantha Dale Oldfield**, Auckland
(NZ); **Edward John Evans**, Auckland
(NZ); **Nathan James Roa**, Auckland
(NZ); **Kate Jayne Chilcott**, Auckland
(NZ); **Craig Karl White**, Auckland
(NZ)(73) Assignee: **Fisher & Paykel Healthcare Limited**,
Auckland (NZ)(**) Term: **15 Years**(21) Appl. No.: **29/866,143**(22) Filed: **Aug. 30, 2022****Related U.S. Application Data**(62) Division of application No. 29/761,321, filed on Dec.
8, 2020, now Pat. No. Des. 965,141, which is a
division of application No. 29/731,944, filed on Apr.
20, 2020, now Pat. No. Des. 907,762, which is a
division of application No. 29/644,094, filed on Apr.
13, 2018, now Pat. No. Des. 885,556.(51) **LOC (14) Cl.** ..... **24-02**(52) **U.S. Cl.**USPC ..... **D24/127**(58) **Field of Classification Search**USPC D24/110–110.6, 127, 128, 143; D29/108,

Primary Examiner — Daniel J Domino*Assistant Examiner* — Lee D. Starr(74) *Attorney, Agent, or Firm* — Knobbe, Martens, Olson
& Bear LLP**CLAIM**The ornamental design for a clip for a gas sampling line, as
shown and described.**DESCRIPTION**FIG. 1 is a front, top and left side perspective view of a clip
for a gas sampling line, showing our new design;
FIG. 2 is a front, bottom, and left side perspective view
thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

The broken lines in the drawings illustrate portions of the
clip for a gas sampling line which form no part of the
claimed design.**1 Claim, 8 Drawing Sheets**(56)
